UNITED STATES PATENT OFFICE.

ERNEST J. AUTREY, OF LOS ANGELES, CALIFORNIA, ASSIGNOR, BY MESNE ASSIGNMENTS, OF ONE-HALF TO RUSSELL M. SIMMONS.

HEAT EXCHANGER.

Application filed September 17, 1925. Serial No. 56,854.

This invention is a device for transferring the heat of one fluid to another; and while in the present embodiment of the invention the device is particularly adapted for raising the 5 temperature of a liquid by the heat from a suitable burner, it will be understood that the novel construction is of general utility for exchange of heat, and may be incorporated in any apparatus for heating or cooling a 10 fluid, such as a condenser, water heater, still, or steam generator.

It is the object of the invention to provide for tortuous passage through the apparatus of the fluid whose temperature is to be 15 changed, with the fluid in intimate relation with the medium adapted to produce the temperature change, thereby providing a rapid exchange of heat and utilizing the temperature changing medium to its maximum efficiency.

More particularly it is the object of the invention to position a baffle chamber in a suitable enclosing annulus, with one fluid passing through the annulus and around the baffle, 25 and the other fluid of different temperature circulating through the baffle chamber and back and forth across the same.

It is a still further object of the invention to provide for circumferential movement 30 through the baffle chamber back and forth around radial fins; and to combine said movement of the flow with circulation thereof back and forth across the baffle chamber in opposite directions.

It is a still further object of the invention to pre-circulate one of the fluids through a shell forming the enclosing annulus of the apparatus, before discharge of said fluid into the baffle chamber; thereby providing for 40 initial exchange of heat between the circulating fluid and the fluid of different temperature passing through the enclosing annulus of the device.

It is a still further object of the invention to provide for tortuous passage of the fluid 45 through the pre-circulating space, and to cause maximum heat radiation in the enclosing annulus of the apparatus between the spaces adapted for circulation of said fluid.

In the drawings which show one practical embodiment of the invention particularly applicable as an instantaneous water heater:

Fig. 1 is a vertical section through the water heater.

Figs. 2 and 3 are transverse sections on the 55 lines 2—2 and 3—3 of Fig. 1.

Fig. 4 is a vertical section through a baffle chamber of the water heater.

Figs. 5 and 6 are transverse sections on the 60 lines 5—5 and 6—6 of Fig. 4.

Fig. 7 is a fragmentary sectional view of the shell 12 showing baffles 18.

The annular shell of the water heater is shown at 1 as a closed hollow structure having 65 a flue 2 on the upper end thereof and preferably supported on lugs 3 in a sleeve 4 having a base 5 extending beneath the shell in spaced relation therefrom, with supporting legs 6 depending from the sleeve. Suitable insulating lining (not shown) may be interposed 70 between the shell and its surrounding sleeve.

A burner which is shown as a gas burner ring 8, is supported on the base 5 below the axial opening which extends through the annular shell 1, and perforations 9 are provided 75 in the lower part of sleeve 4 and in the base 5 for supplying air to the burner.

A second closed hollow shell 12 having an axial opening extending therethrough, may 80 be concentrically mounted in the axial opening extending through shell 1, the shell 12 being supported by studs 13 projecting from shell 1, and spaced from said outer shell so as to form a heat passage between the shells as well as through the central opening extending 85 through the inner shell.

A baffle chamber 14 is mounted in the central heat passageway which extends through the device; and in practice a plurality of said baffle chambers are preferably employed, and 90 are arranged in spaced superimposed relation in the central opening extending through the annular shells, and may also be disposed in the flue 2 projecting above the shells.

The lowermost baffle chamber which is suitably spaced above the burner 8, is of relatively small diameter so as to leave an appreciable heat passageway between the same and the surrounding shell, and the superimposed 100 baffle chambers are preferably of gradually increasing diameter so as to finally form a materially restricted heat passageway around the baffle chambers.

The shell 1, as well as the shell 12 when 105 the latter is also provided in the apparatus, is a pre-heater from which the water is discharged to the uppermost of baffle chambers

14 for circulation downwardly through the succeeding lower baffle chambers.

As an instance of this arrangement a water supply pipe 15 communicates with shell 1, 5 and the water is discharged from said shell at its opposite side. Before the water then enters the upper baffle chamber 14, it passes through shell 12, when the latter is included in the construction; and for this purpose the 10 water discharge from shell 1 communicates with shell 12 through a pipe 16, and a discharge pipe 17 leads from the opposite side of shell 12 to the upper baffle chamber 14, from whence short lengths of said discharge 15 pipe connect the succeeding lower baffle chambers, and the discharge pipe finally projects beyond the heater from the lowermost baffle chamber.

The water is adapted for tortuous passage 20 through the pre-heating shells and flows around both sides of the shells from their intake to their discharge ports. As an instance of this arrangement the intake and discharge ports are adjacent the upper ends of the 25 shells, and circumferentially spaced vertical radial fins 18 are mounted in the shells, with said fins alternately terminating short of the ends of the shells at their opposite ends, so that the water is forced to flow up and down 30 around the fins.

As the water flows through the baffle chambers 14, it is also subjected to a tortuous flow and is spread out by the interior construction of the baffle chambers as shown in Figs. 4 to 35 6. Each of the baffle chambers is an upright closed cylindrical structure having a transverse horizontal partition 20 medially thereof. Ends 17^a and 17^b of the various sections of discharge pipe 17 extend into the spaces 40 above and below the medial partition respectively, the pipe ends being centrally disposed in the baffle chamber and closed by the partition 20, and having vertically aligned lateral ports 21^a and 21^b opening through said pipe 45 ends.

Upright radial fins are provided in the spaces at opposite sides of partition 20, and extend from the partition to the top and bottom of the baffle chamber, with certain of said 50 fins shown at 22^a and 22^b in vertical alinement at one side of ports 21^a and 21^b, and extending from pipe ends 17^a and 17^b to the periphery of the baffle chamber. The remaining fins 23^a and 23^b at opposite sides of 55 partition 20 alternately terminate at opposite ends short of pipe ends 17^a—17^b and the periphery of the baffle chamber, so that in the space above partition 20, the water circulates in the direction shown by the arrows in Fig. 6, for discharge through a port 24 in partition 20 in back of fins 22^a—22^b. The water thus enters the space below partition 20, and circulates back and forth around fins 23^a and 60 in the opposite circumferential direction as shown by the arrows in Fig. 6, for final dis- 65

charge through ports 21^b into the pipe end 17^b.

In order to increase the radiation of heat as it passes through the annular space between shells 1 and 12, baffle means may be 70 mounted in said heat passageway, and in the present instance are shown as hollow perforated cylinders 25, preferably of a suitable clay, suspended from the studs 13.

The heat is preferably brought into intimate contact with the baffle chambers 14 by means of transverse baffle plates 26, which have supporting legs 27 resting upon the respective baffle chambers for spacing the baffle plates slightly above the baffle chambers. 80 The baffle plates extend to the wall of shell 12 and are provided with central openings 28 around the pipe 17. The heat in the central passageway of the heater thus circulates across the top of the respective baffle chambers in intimate contact therewith and is discharged through openings 28 for similar circulation across the next upper baffle chamber.

The construction as thus described provides for tortuous flow of the water and spreads the water in a thin film over a relatively large surface which is directly in contact with the heating medium. Furthermore the passage of the heated gas is retarded and diverted in order to obtain maximum radiation and transfer of heat units.

I claim:

1. Heat transferring means comprising a structure defining a central passageway for a fluid, a flow circulating means in the central passageway spaced from the wall of the structure and adapted for flow of a fluid of different temperature through the flow circulating means, and a plurality of elongated perforated baffles extending lengthwise of the central passageway in the space between the flow circulating means and the wall of the structure.

2. Heat transferring means comprising a structure defining a central passageway for a fluid, radially spaced annular hollow shells in the central passageway, baffle means between the annular shells, a flow discharge means in the central passageway, and inlet and outlet connections between the hollow shells and the flow discharge means arranged for flow of a fluid of different temperature successively through the hollow shells and thence through the flow discharge means for discharge distinct from the entrance of said fluid.

3. Heat transferring means comprising a structure defining a central passageway for a fluid, a plurality of baffle chambers spaced lengthwise of the passageway and arranged for flow of a fluid of different temperature through the succeeding baffle chambers, the baffle chambers being spaced from the wall of the structure with said space increasingly restricted at the succeeding baffle chambers in

the direction of the flow through the passageway.

4. Heating transferring means comprising a structure defining a central passageway for a fluid, a hollow shell in the passageway, a baffle chamber in the passageway, means for causing flow of a fluid of different temperature through the hollow shell and thence through the baffle chamber for discharge distinct from the entrance of said fluid, a transverse partition in the baffle chamber, an inlet at one side of the partition, an outlet from said side of the partition forming an inlet at the opposite side of the partition, a plurality of radial fins in the baffle chamber at each side of the partition, one of said fins at each side of the partition forming a well between the inlet and outlet at said side of the partition, and the other fins at each side of the partition alternately terminating short of the baffle chamber at opposite ends.

5. Heat transferring means comprising a structure defining a central passageway for a fluid, a hollow shell in the passageway, and a plurality of baffle chambers spaced lengthwise of the passageway and arranged for flow of a fluid of different temperature through the hollow shell and thence through the succeeding baffle chambers, the baffle chambers being spaced from the wall of the structure with said space increasingly restricted at the succeeding baffle chambers in the direction of the flow through the passageway.

6. Heat transferring means comprising a structure defining a central passageway for a fluid, a hollow annular shell in the passageway having an inlet and an outlet adapted for flow of a fluid of different temperature through the hollow shell, means in the hollow shell between the inlet and outlet for causing flow of said fluid successively in opposite directions lengthwise of the shell, and a flow spreading means in the passageway adapted for flow from the outlet of the hollow shell through the flow spreading means for discharge distinct from the entrance of said fluid to the hollow shell.

7. Heat transferring means comprising a shell including an inner and outer wall forming a jacket space, the inner wall defining a central passageway for a fluid, an inlet and an outlet adapted for flow of a fluid of different temperature through the jacket space, means in the jacket space for causing tortuous flow therethrough, and a flow spreading means in the central passageway communicating with the outlet from the jacket space.

8. Heat transferring means comprising a structure defining a central passageway for a fluid, a hollow annular shell in the passageway, said hollow shell having an inlet and an outlet adapted for flow of a fluid of different temperature through the hollow shell, means in the hollow shell between the inlet and outlet for causing tortuous flow of fluid through the

hollow shell, and a flow spreading means in the central passageway adapted for flow from the outlet of the hollow shell through the flow spreading means for discharge distinct from the entrance of said fluid to the hollow shell.

9. Heat transferring means comprising a structure defining a central passageway for a fluid, a hollow annular shell in the passageway, said hollow shell having an inlet and an outlet adapted for flow of a fluid of different temperature through the hollow shell, means in the hollow shell for causing tortuous flow of the fluid therethrough, a baffle chamber in the central passageway, a transverse partition in the baffle chamber having a port opening therethrough, an inlet at one side of the partition communicating with the outlet from the hollow shell, said port forming an outlet from said side of the partition and an inlet for the opposite side of the partition, an outlet from said opposite side of the partition, and a radial partition at each side of the transverse partition in the same circumferential direction beyond the partition port and forming a wall between the inlet and outlet at each side of the transverse partition to cause flow of the fluid around the baffle chamber in opposite circumferential directions at the respective sides of the transverse partition.

10. Heat transferring means comprising a structure defining a central passageway for a fluid, a hollow annular shell in the passageway, said hollow annular shell having an inlet and an outlet adapted for flow of a fluid of different temperature through the hollow shell, means in the hollow shell for causing tortuous flow of the fluid therethrough, a baffle chamber in the central passageway, a transverse partition in the central passageway, an inlet at one side of the partition communicating with the outlet from the hollow shell; an outlet from said side of the partition forming an inlet for the opposite side of the partition, an outlet from said opposite side of the partition, and a plurality of radial fins in the baffle chamber at each side of the partition, one of said fins at each side of the partition forming a wall between the inlet and outlet at said side of the partition, and the other fins at each side of the partition alternately terminating short of the baffle chamber at opposite ends.

11. Heat transferring means comprising a structure defining a central passageway for a fluid, a hollow annular shell in the passageway, a diametrically opposite inlet and outlet for the hollow shell adapted for flow of a fluid of different temperature equally around both sides of the interior of the hollow shell, means in the hollow shell for causing tortuous flow of the fluid therethrough, and a flow spreading means in the central passageway communicating with the outlet from the hollow shell.

12. Heat transferring means comprising a structure defining a central passageway for a fluid, a hollow annular shell in the passageway, said hollow shell having an inlet and 5 an outlet adapted for flow of a fluid of different temperature through the hollow shell, a flow spreading means in the central passageway communicating with the outlet from the hollow shell, and baffle means in the central 10 passageway, the said hollow shell having means for causing tortuous flow of the fluid therethrough.

13. Heat transferring means comprising a

structure defining a central passageway for a fluid, radially spaced hollow annular shells 15 in the central passageway, a flow spreading means in the central passageway, and inlet and outlet connections between the hollow shells and the flow spreading means adapted for flow of a fluid of different temperature 20 successively through the hollow shells and the flow spreading means.

In testimony whereof I have affixed my signature to this specification.

ERNEST J. AUTREY.
